ANNEALING APPARATUS

Roy E. Carter, Warren, Ohio

Application August 15, 1946, Serial No. 690,635

4 Claims. (Cl. 263—43)

1

My invention relates to processes and apparatus for annealing metal sheets and particularly steel sheets in a sealed furnace compartment formed by outer furnace walls within which a stack of the metal sheets is located and constitutes a mass of metal over which is placed a sealed inner cover. Heat is introduced into the furnace compartment by means of burners located in the outer furnace side walls, the burners being supplied with fluid fuel, usually gas.

Prior to the present improvements, in such an annealing furnace there has been a non-uniform heating of the stack of metal sheets, the upper portions of the stack reaching the desired temperature before the lower portions, and a prolonged heating period has been required to bring the lower portions of the stack of metal sheets up to the desired temperature. The reasons for the non-uniform heating of the stack of metal sheets or charge in the usual annealing furnace include flame and heat distribution in the furnace compartment which in the early part of the heating cycle of any particular charge passes by the lower portions or bottom of the furnace compartment, and the bottom of the charge, and first heats up the top of the furnace compartment and charge.

For example, in many usual portable annealing furnaces each burner has a horizontal direction of flame motion from the nozzle of the burner in one of the outer furnace side walls, and this horizontally directed flame strikes a baffle tile or catalyst having a vertical face in the furnace compartment immediately in front of the burner nozzle. The horizontally directed flame strikes the vertical baffle face and rises immediately towards the upper portions of the furnace compartment with slight heating effect upon the bottom of the charge. Moreover, such baffles mounted directly in front of a burner ejecting a horizontally directed flame are often broken or knocked out.

The objects of the present improvements include the provision of improved processes and apparatus for effecting in an annealing furnace of the type described uniform and rapid heating of a stack of metal sheets from the bottom to the top, the heating of the stack of metal sheets or charge being initiated at the bottom of the charge from the beginning and throughout the heat cycle, whereby an equilibrium of top and bottom temperatures in the furnace compartment and charge is reached very rapidly, and a relatively short heat cycle for the complete annealing or heat treatment is attainable, with a consequent saving in fuel consumption, as compared with usual annealing or heat treating processes and apparatus.

Further objects of the present improvements include the provision of annealing furnace apparatus including improved and novel details of construction and arrangement by the operation

of which the annealing or heat treating of the stack of metal sheets is effected in an improved manner as compared with prior practice.

The foregoing and other objects are attained by the improved processes, process steps, apparatus, parts, combinations, and sub-combinations of the present invention, the nature of which is set forth in the following general statement, and preferred examples and embodiments of which together with their mode of use are set forth in the following description, and which are particularly and distinctly pointed out and set forth in the appended claims forming part hereof, or in claims which may originate herein.

15 The nature of the processes of the present improvements may be stated in general terms as including in a furnace compartment for annealing and the like, breaking up and catalyzing a flame jet at the bottom of the compartment so as to initiate heating at the bottom and rapidly 20 attain temperature equilibrium from bottom to top of the furnace compartment and charge therein.

25 The nature of the apparatus of the present improvements may be stated in general terms as including walls forming a furnace compartment, a flame jet target wall in a lower portion of the furnace compartment, and means for impinging a flame jet against the target wall, the flame jet and target wall being arranged with respect to each other so as to initiate heating and flame distribution at the bottom of the furnace compartment and charge therein.

30 By way of example, embodiments of the improved apparatus and parts hereof adapted for carrying out the improved processes and process steps hereof are illustrated in the accompanying drawings forming part hereof in which

35 Figure 1 is a fragmentary transverse vertical cross section as on line 1—1, Fig. 2 of an annealing furnace including the present apparatus improvements and adapted for carrying out the improved process steps hereof;

40 Fig. 2 is a reduced vertical longitudinal section thereof as on line 2—2, Fig. 1; and

45 Fig. 3 is an enlarged fragmentary view similar to Fig. 1.

50 In Figs. 1 and 3 the stack of metal sheets and the inner cover are shown, while in Fig. 2 the furnace is shown without either the stack of metal sheets or the inner cover.

Similar numerals refer to similar parts throughout the drawings.

55 The improved annealing furnace indicated generally by 10 includes a composite rectangular bottom wall indicated generally by 11, opposite laterally spaced composite side walls indicated generally by 12a and 12b, opposite longitudinally spaced composite end walls indicated generally by 12c and 12d, and a composite rectangular top wall indicated generally by 13.

60 Side and end portions of the walls 11, 12a, 12b,

12c, 12d, and 13 are in sealing engagement with each other when the furnace is in use, and form a sealed furnace compartment 14. As shown and preferably, the composite bottom wall 11 is separable from the side and end walls 12a, 12b, 12c, and 12d, and the top wall 13, which are connected with each other and carried by a structural framework indicated generally by 15, having a central upper lifting yoke 16, whereby the side and end walls 12a, 12b, 12c, and 12d and the top wall 13 may be lifted bodily from the bottom wall 11, by means of a crane.

In other words, the connected side and end walls 12a, 12b, 12c, and 12d, and top wall 13 form an inverted box having a lower opening, bounded by the lower faces of the side and end walls 12a, 12b, 12c, and 12d, these lower faces seating upon top border portions of the rectangular bottom wall 11 to form the sealed furnace compartment 14 as illustrated, and there being usual sand seal means indicated generally by 17 at the joints between the lower faces of the side and end walls 12a, 12b, 12c, and 12d, and the bottom wall 11.

The composite bottom wall 11 as shown includes a lower metal pan 18 opening upwardly and preferably formed of sheet metal, and preferably as shown being provided with inner downwardly opening rectangular reinforcing channel ribs 19. In the pan 18 are located a plurality of horizontal layers of refractory brick 20. On top of a top layer of the refractory brick 20 bounded by the channel ribs 19, there is supported a plurality of laterally extending side by side steel rails 21 on the top of which is supported a rectangular steel plate 22, the rails 21 forming a plurality of horizontal flues 21—1 therebetween.

When the furnace is in use as shown in Figs. 1 and 3, a stack of metal sheets 23 are supported on the steel plate 22. The improved furnace 10 is particularly adapted for use in annealing steel sheets, and the metal sheets 23 may therefore in many instances be steel sheets. An inner inverted box cover 24, usually made of sheet steel, is placed over the stack of metal sheets 23, and the lower edges of the side and end walls of the inner box cover 24 seat on upper faces of the channel ribs 19, and form therewith and with side walls 26a and 26b and end walls 26c and 26d each projecting upwardly from a lower layer of the brick 20 above the top of the top layer of brick 20 in the composite bottom wall 11, a channel filled with sand 25 which provides a sand seal for the inner cover 24.

The inverted box inner cover 24 includes opposite spaced side walls 27a and 27b, the inner cover side wall 27a being opposite the outer furnace side wall 12a, and the upwardly projecting wall 26a is laterally spaced from and extends longitudinally between the outer furnace wall 12a and the inner cover wall 27a. Similarly, the inner cover wall 27b is located opposite the outer furnace wall 12b and the upwardly projecting wall 26b is laterally spaced from and extends longitudinally between the walls 27b and 12b.

The upwardly projecting wall 26a constitutes a burner target wall, and for the purposes of the present improvements preferably is provided with an outer longitudinally extending side deflector face 28a which slopes from bottom to top towards the inner cover wall 27a. Similarly, the upwardly projecting wall 26b constitutes a burner target wall and is provided with an outer longitudinally extending side deflector face 28b which

slopes from bottom to top towards the inner cover wall 27b.

The composite side and end walls 12a and 12b each include as shown an outer sheet metal wall 29 and an inner refractory brick lining wall 30. The composite top wall 13 as shown includes an inner refractory brick arch wall 31 and an outer refractory cover wall 32.

In the lower portion of the outer furnace side wall 12a are mounted a plurality of high velocity gas burners each indicated generally by 33, and similarly a plurality of the burners 33 are mounted in the lower portion of the outer furnace side wall 12b. Each burner 33 includes an inner elongated nozzle tube 34, preferably a venturi, having a longitudinal axis 35 which is the axis of the flame jet emitted from the burner tube 34 within the furnace compartment 14. Each tube and flame jet axis 35 slopes from the top downwardly towards the bottom wall 11 and intersects the deflector face 28a or 28b of one of the target walls 26a or 26b. Each burner 33 is a high velocity fluid fuel burner, preferably supplied with gas through usual supply pipe line means 36 as shown in Fig. 3. A pilot burner indicated generally by 37 is preferably provided for each high velocity burner 33.

In the operation of the improved annealing furnace 10 for carrying out the improved processes hereof the flame jet from each burner 33 strikes against one of the deflector faces 28a or 28b of one of the target walls 26a or 26b, where the flame jet is broken up and catalyzed and immediately initiates heating of the bottom of the furnace compartment and of the stack of metal sheets or charge 23, the target walls 26a and 26b rapidly rising in temperature and heat being transmitted by conduction from the target walls 26a and 26b and through the refractory brick 20 and metal channel ribs 19 in the composite bottom wall 11 to the side by side rails 21 with the horizontal flues 21—1 therebetween. These flues 21—1 have open ends and the gases within the inner cover 24 circulate through the horizontal flues under 45 and then around the sheet stack or charge 23, and the heat transmitted to the side by side rails 21 is in turn immediately transmitted to the bottom of the sheet stack or charge 23. The broken up flame jets striking the deflector faces 28a and 28b of the target walls 26a and 26b on the outside 50 of the inner cover are distributed throughout the furnace compartment 14 between the outer furnace walls and the inner cover 24, the flow of the distributed flame or combustion gases being 55 upwardly along the side and end walls of the inner cover 24 across the lower face of the top wall 13, and down along the inner faces of the outer cover side and end walls 12a 12b, 12c, and 12d.

60 The heat flow and distribution in the charge and in the combustion gases in the furnace compartment 14 is thus initiated at the bottom of the charge and of the furnace compartment and very quickly reaches an equilibrium condition 65 from bottom to top, so that time of the heat cycle required for each charge is reduced considerably as compared with usual practice, and a substantial saving in fuel is effected.

It is further noted that the rails 21 and plate 70 22 forming the flues 21—1, and the sheet stack or charge 23 supported on the plate 22, are all in a sealed inner compartment formed by the inner cover 24 and the composite bottom wall 11 and the sand seal therebetween. This sand seal, as 75 above stated, is formed by sand 25 filling the

channel formed by the lower edges of the side and end walls of the inner box cover 24, and by upper faces of the channel ribs 19 on which the lower edges of the side and end walls of the inner box cover 24 are seated, and by the upwardly projecting burner target side walls 26a and 26b and the upwardly projecting end walls 26c and 26d.

Within this sealed inner compartment the above described heating of the bottom of the sheet stack or charge 23 and circulation of the gases under and then around the sheet stack or charge 23 takes place simultaneously with the distribution of combustion gases from bottom to top of the outer furnace compartment 14 and the flow of the combustion gases therein produced by the flame jets of the burners 33 being directed downwardly and inwardly and striking the deflector faces 28a and 28b of the target walls 26a and 26b.

The furnace 10 is preferably provided with exhaust means for the burned gases in the furnace compartment 14, and the exhaust means preferably include a plurality of covered intake heads, each indicated generally by 38 and located in the furnace bottom wall 11. These intake heads 38 communicate through flues below the furnace bottom wall 11 to a common stack, and eliminate the discharge of the spent combustion gases into the building in which the furnace 10 is located, as is usual practice. The discharge of the gases of combustion from annealing furnaces directly into the building in which they are located is objectionable, particularly to the operators of the travelling cranes which are used to raise and lower the outer furnace covers and the stacks of steel sheets, in charging and discharging the furnaces.

Each intake head 38 as shown includes an upper dome cover 39 and a vertically extending tube 40 having an upper end portion protruding above the furnace bottom wall 11 and into the lower portion of the furnace compartment 14, each cover 39 extending over with substantial clearance and being supported on the upper extremity of the associated tube 40. Each tube 40 constitutes a flue tube extending vertically through the furnace bottom wall 11, and as shown being made of metal. Each dome cover 39 has its lower edge located closely adjacent the top of the bottom wall 11, whereby the exhaust gases are forced to travel along the bottom wall to exit through the tube 40.

The steps and embodiments of the present improvements described herein are by way of example, and the scope of the present invention is not limited to the same or to the particular details thereof but is commensurate with any and all novel subject matter contained herein which may at any time properly come under the United States patent laws be set forth in the claims hereof or originating herein, and the elements of any such claims are intended to include their reasonable functional and structural equivalents.

I claim:

1. In a furnace for annealing and the like, walls forming an inner sealed compartment and walls forming an outer sealed compartment extending around walls of the inner compartment, the compartments having a common bottom wall including a plurality of members in heat conducting association with each other, some of the heat conducting members forming flues within the inner compartment, the flue forming common bottom wall members within the inner compartment being adapted to support a charge of material, and means for introducing and directing a flame jet downwardly into the outer compartment so as to strike the common bottom wall in the outer compartment adjacent another wall of the inner compartment.

2. In a furnace for annealing and the like, walls forming an inner sealed compartment and walls forming an outer sealed compartment extending around walls of the inner compartment, the compartments having a common bottom wall including a plurality of members in heat conducting association with each other, some of the heat conducting members being spaced from each other within the inner compartment, the spaced common bottom wall members within the inner compartment being adapted to support a charge of material, and means for introducing and directing a flame jet downwardly into the outer compartment so as to strike the common bottom wall in the outer compartment adjacent another wall of the inner compartment.

3. In a furnace for annealing and the like, walls forming an inner sealed compartment and walls forming an outer sealed compartment, the compartments having a common bottom wall including a plurality of members in heat conducting association with each other, some of the heat conducting members being spaced from each other within the inner compartment, the spaced common bottom wall members within the inner compartment being adapted to support a charge of material, and means for introducing and directing a flame jet downwardly into the outer compartment so as to strike the common bottom wall in the outer compartment adjacent another wall of the inner compartment.

4. In a furnace for annealing and the like, walls forming an inner sealed compartment and walls forming an outer sealed compartment, the compartments having a common bottom wall including a plurality of members in heat conducting association with each other, some of the heat conducting members being spaced from each other within the inner compartment, the spaced common bottom wall members within the inner compartment being adapted to support a charge of material, one or more of the heat conducting members of the common bottom wall projecting upwardly in the outer compartment adjacent a wall of the inner compartment, the upwardly projecting common bottom wall members constituting a target, and means for introducing and directing a flame jet downwardly into the outer compartment so as to strike the heat conducting target members of the common bottom wall.

5. In a furnace for annealing and the like, walls forming an inner sealed compartment and walls forming an outer sealed compartment extending around walls of the inner compartment, the compartments having a common bottom wall including a plurality of members in heat conducting association with each other, some of the heat conducting members being spaced from each other within the inner compartment, the spaced common bottom wall members within the inner compartment being adapted to support a charge of material, and means for introducing and directing a flame jet downwardly into the outer compartment so as to strike the common bottom wall in the outer compartment.
